UNITED STATES PATENT OFFICE.

JULIUS RICHARD, OF BISBEE, ARIZONA TERRITORY, ASSIGNOR OF THREE-EIGHTHS TO FRANK DU CACHER, AUGUST JOERSS, FRED COLEMAN, AND OTTO VON KANEL, OF SAME PLACE.

RAILROAD-SPIKE.

SPECIFICATION forming part of Letters Patent No. 594,757, dated November 30, 1897.

Application filed December 5, 1896. Serial No. 614,601. (No model.)

To all whom it may concern:

Be it known that I, JULIUS RICHARD, a citizen of the Republic of France, residing at Bisbee, in the county of Cochise and Territory 5 of Arizona, have invented certain new and useful Improvements in Railroad - Spikes; and I do hereby declare the following to be a full, clear, and exact description of the invention, such as will enable others skilled in the 10 art to which it appertains to make and use the same.

This invention relates to railroad-spikes, and has for its object to provide a simple, cheap, and efficient spike which when driven 15 into the tie will be adapted to spread and obtain a firmer hold on the tie than by the ordinary construction.

The improved spike is divided longitudinally and beveled as to its separated portions, so that as the spike is driven down the 20 said portions are caused to spread away from a central line, thereby causing the spike to become more firmly embedded in the tie, and the said spike also comprises near its head 25 cheek portions and also a laterally-projecting lug forming a sustaining-shoulder, all of which will be hereinafter described.

The invention consists in a railroad-spike embodying certain novel features and details 30 of construction, as hereinafter fully described, illustrated in the drawings, and incorporated in the claim.

In the accompanying drawings, Figure 1 is a perspective view of the improved railroad-spike. Fig. 2 is a section through the tie, showing the position of the spike when driven 35 to place. Fig. 3 is a side elevation of the spike.

Similar numerals of reference designate corresponding parts in the several figures of the 40 drawings.

The improved railroad-spike contemplated in this invention resembles in its general outline an ordinary railroad-spike. This spike 45 comprises the body or shank portion 1, which is provided at one end with an enlarged head 2, having the usual overhanging or laterally-projecting lip 3 for engaging the base of a railway-rail, or the fish-plate, which connects

to the contiguous ends of the rails in a manner well understood. 50

For the purpose of carrying out this invention a round hole 3' is formed in the spike, extending transversely therethrough at a point about an inch, more or less, below the 55 head 2, and this hole extends in a direction at right angles to the rail when the spike is in place. From the hole 3' the body or shank of the spike is divided longitudinally, said division extending to the point or end of the 60 spike and opening out through it, whereby the body or shank of the spike is divided into two equal portions firmly connected or formed integrally with the head 2. At their extremities these divided portions are beveled on their inner faces downward and outward, as indicated at 4, whereby as the spike 65 is driven home the divided portions are caused to separate or be deflected in opposite directions, assuming a position shown in 70 Fig. 2, and thereby serving to prevent the displacement of the spike.

Just under the head 2 the body or shank 1 is provided with cheeks 5, formed by thickening the spike on each side at a point on 75 each side of the transverse hole 3'. These cheeks not only strengthen the body of the spike adjacent to the point where the same is weakened by the formation of the hole 3', but they also serve to snugly fill the mouth 80 of the opening in the tie formed by driving the spike therein. On that side of the spike opposite to the side from which the lip 3 projects is a laterally-projecting lug 6, which forms a sustaining-shoulder, the same being 85 adapted to be driven partly into the tie, so as to become firmly seated and serving to prevent the spike from being thrust away from the base-flange of the rail when subjected to heavy strain. 90

The under side of the laterally-projecting lug 6 is concaved, as clearly shown, so that as the spike is driven to place in the tie it will be at the same time forced toward the rail for causing the lip 3 to engage more 95 firmly over the base-flange of the rail.

From the foregoing description it will be seen that a very simple and efficient spike is

provided, which obtains a much firmer hold on the tie than an ordinary spike and which is especially useful on curves where the greatest strain is brought to bear on the spike.

5 The object in making the transverse opening 3' round is to afford no angular termination to the longitudinal division in the spike, which would increase the liability of the spike to split entirely in two.

10 The spike is formed from malleable metal, so that it will spread without breaking.

Having thus described the invention, what is claimed as new is—

As an article of manufacture, a railroad-
15 spike provided below its head with a round transverse opening extending therethrough, the shank of the spike being divided longitudinally and centrally from said opening to the point of the spike where the divided por-

tions are beveled reversely upon their inner 20 surfaces, thickened cheek portions at each side of the spike extending from the transverse opening upward toward the head, and a rearwardly-projecting lug forming a sustaining-shoulder and having a curved and 25 concave lower surface whereby in driving the spike, said shoulder or lug serves to force the head of the spike into solid engagement with the base of the rail, substantially as described.

30 In testimony whereof I have signed this specification in the presence of two subscribing witnesses.

JULIUS RICHARD.
